UNITED STATES PATENT OFFICE.

ROBERT LEE BOWMAN, OF KNOXVILLE, TENNESSEE.

CONDUCTOR FOR MINE EXPLOSIVES.

1,395,792.

Specification of Letters Patent.

Patented Nov. 1, 1921.

Application filed January 19, 1921. Serial No. 438,417.

To all whom it may concern:

Be it known that I, ROBERT L. BOWMAN, a citizen of the United States, residing at Knoxville, in the county of Knox and State 5 of Tennessee, have invented a new and useful Conductor for Mine Explosives, of which the following is a specification.

This invention relates to conductors whereby by miners are enabled to place charges of 10 explosives into holes drilled therefor without experiencing accidents, the loss of time and material resulting from the usual methods followed.

Heretofore it has been the practice to tear 15 off a required length of paper from a roll and form and fill the same with an explosive, and insert the filled shell into the hole. Very often the shell buckles on account of the roughness or crevices in the strata before it reaches the innermost portion of the 20 hole; and at other times it will bulge open and cause waste of the explosive, and great danger in recharging the hole on account of the bit striking sulfur and thereby causing 25 a spark.

It is an object of the present invention to provide a conductor of a predetermined size in which a shell of the usual or any preferred construction can be placed and conveyed 30 directly to any portion of the hole without danger of buckling and without danger of being misplaced or of losing any of the explosive.

Another object is to provide a device of 35 this character made up of separable sections whereby one part of the conductor can be opened easily to receive the charge and subsequently closed so as to hold the charge during its insertion into the hole.

Another object is to provide a conductor 40 a portion of which can be utilized as a spoon should it be desired to place an explosive back in a hole without the use of a shell.

Another object is to provide a conductor 45 a portion of which is telescopic and which portion can separately be used as a casing or conductor to place an explosive back in a hole.

A still further object is to provide a conductor 50 which may be used as a mandrel and which is very simple, durable and compact in construction and which can be easily manipulated.

With the foregoing and other objects in 55 view which will appear as the description proceeds, the invention resides in the combi-

nation and arrangement of parts and in the details of construction hereinafter described and claimed, it being understood that, within the scope of what is claimed, changes in 60 the precise embodiment of the invention shown can be made without departing from the spirit of the invention.

In the accompanying drawings the preferred form of the invention has been shown. 65

In said drawings—

Figure 1 is a plan view of the device.

Fig. 2 is a longitudinal section.

Fig. 3 is a transverse section.

Fig. 4 is a detail view of a combined cap 70 and cup.

Referring to the figures by characters of reference 1 designates the main section of the conductor, the same being substantially semicylindrical and hollow. One end of this 75 section is closed as indicated at 2 and extending across the open face of the section at the closed end thereof is a flat wall 3 having a slot 4 therein adjacent its free edge. An opening 5 is formed in the wall 2 at the 80 center of the arc defined by the arcuate wall of the section and another opening 6 is formed in said wall as shown. Additional openings 7 and 8 are formed in the wall 2 and in the wall 3, these two openings being 85 designed to receive the offset end 9 of a holding rod or handle 10.

A removable section 11 is mounted on the section 1 and is substantially semicylindrical and hollow. This section has one end closed 90 and adapted to abut against the wall 3 while its other end is open and is designed to lie flush with the open end of the section 1. A curved tongue 12 is extended from the closed end of the section 11 and is insertible into the slot 4 so as to hold the sections 1 and 11 95 properly assembled at one end. It is possible, however, by swinging the section 11 away from the section 1, to disengage the tongue from the slot. A telescopic tube 13 is slidable on the sections 1 and 11 and is adapted to move forward or backward as desired against a rib or shoulder 14 on the outer faces of the sections adjacent their free ends so as to hold said sections together as shown in the drawings. By slipping the tube 13 up toward the closed end of the section 1, however, the section 11 is released and can be swung away from section 1 and detached therefrom.

Slidably mounted between the sections 1 and 11 is a plunger or follower 15 having a 100

105

110

fuse receiving recess 16 in its periphery. This follower has a stem 17 slidable within the opening 5 and detachably engaged by an extension handle 18. It is to be understood, 5 also, that an extension handle 19 may be connected to the rod 10.

In using this device for the purpose of placing a charged shell or a granular explosive in any portion of a hole, the plunger 15 10 is moved against the closed end of the sections 11, a fuse is placed in the opening 6 and the recess 16, and a wad may be pressed against the plunger 15. The charged shell or explosive is then placed in the conductor 15 and another wad may be forced into the open end of said conductor. The entire device is then inserted into the hole until it reaches the desired portion thereof, the extension handles 18 and 19 being employed if 20 necessary. The plunger 15 is then held stationary while the operator pulls on the rod 10 so as to cause the conductor sections 1 and 11 to slide off of the charge after which the entire device is withdrawn from the hole and 25 the charge tamped in the usual way. Obviously one or more charges can be placed in the same hole by means of this device and, instead of placing a shell in the conductor the explosive can be positioned therein without 30 the shell. Furthermore by removing the section 11 and the ring 13 the section 1 can be employed as a spoon for placing an explosive back in an opening that has been drilled.

When the conductor is not in use a graduated cup 20 can be employed to close the open end thereof, it fitting over said end like a cap. At other times the cup can be used to measure the explosive placed in the conductor. 35

40 It will be noted that the tube 13 is slit longitudinally so as to be rendered resilient and one of the slits, indicated at 21 is provided with notches 22 for receiving a latch 23 whereby the tube can be drawn longitudinally along the conductor and placed in engagement with a latch at any desired point.

What is claimed is:—

1. A device of the class described including hingedly connected sections, a follower 50 slidably mounted between the sections, and means extending continuously around the connected sections for holding them against relative movement.

2. A device of the class described includ-

ing hingedly and detachably connected sections, a follower slidably mounted between the sections, and means extending continuously around the sections for holding them against relative movement. 55

3. A device of the class described including hingedly and detachably connected sections and a follower slidably mounted between the sections, and handles extending along lines parallel with but spaced from the longitudinal axis of the space between 60 the sections and connected to the follower and to one of the sections respectively. 65

4. A device of the class described including hingedly and detachably connected sections, a follower slidably mounted between 70 the sections, and a sleeve movably engaging the sections for holding them against relative movement.

5. In a device of the class described the combination with opposed hingedly and detachably connected sections coöperating to constitute a conductor, and means movably engaging the sections for holding them assembled, of a follower slidably between the sections, a handle slidably mounted in one 75 end of one of the sections and connected to the follower at a point removed from the center of the follower, and a handle detachably connected to one end of one of the sections, both of said handles being parallel 80 with and spaced from the longitudinal axis of the device, the follower handle constituting means for holding said follower against 85 rotation between the sections. 90

6. A device of the class described including a hollow section closed at one end and having a slotted flat wall adjacent said end, another hollow section closed at one end and disposed oppositely to the first named section, a tongue extending therefrom and engaging the slotted wall and constituting a detachable hinged connection between the sections, a ring slidable upon the sections, a follower slidable between the sections, and means for holding the follower against 95 movement during the movement of the sections relative thereto. 100

In testimony that I claim the foregoing as my own, I have hereto affixed my signature in the presence of a witness.

ROBERT LEE BOWMAN.

Witness:

Ivy E. SIMPSON.
